DUPLICATING APPARATUS

John W. Hernlund, La Grange, Ill., assignor to
 Ditto, Incorporated, Chicago, Ill., a corporation
 of West Virginia

Application August 13, 1934, Serial No. 739,596

2 Claims. (Cl. 101—131)

The invention relates to duplicating apparatus and has for one of its objects the provision of a compact duplicating device which will be simple in construction and relatively inexpensive to manufacture.

One form of the invention is embodied in a duplicating device of the hectograph type. The device comprises a flat platen or bed member stamped from sheet metal, the sheet metal being formed to provide side members which will support it on any suitable object such as a stand, a table, or the equivalent. One end of the sheet metal platen or bed member is provided with integral tongues or lugs engageable with pockets formed in a reenforcing strip which is secured to one end of a hectograph band. The other end of the hectograph band is provided with a reenforcing strip of similar construction and the pockets of the latter strip are engageable by spring-pressed bars mounted beneath the platen or bed member, the construction being such that the spring-pressed bars draw the hectograph band taut over the platen.

The means provided for attaching the hectograph band to the platen and for drawing it taut upon the platen is simple in construction and are constructed so that the hectograph band may be positioned upon the platen in its correct position with very little effort on the part of the operator.

Other advantages will become apparent as the following detailed description progresses, reference being had to the accompanying drawings, wherein—

Fig. 1 is a plan view of a duplicating device which embodies the invention.

Fig. 2 is a longitudinal section taken on line 2—2 of Fig. 1.

Fig. 3 is a transverse section taken on line 3—3 of Fig. 1.

Fig. 4 is an enlarged fragmentary section taken on line 4—4 of Fig. 1.

Fig. 5 is a bottom plan view of the hectograph band shown in Fig. 1.

Fig. 6 is an enlarged fragmentary section taken on line 6—6 of Fig. 5, and

Fig. 7 is an enlarged fragmentary section taken on line 7—7 of Fig. 1.

Referring to the drawings wherein a preferred embodiment of the invention is illustrated, the reference character 10 designates generally a platen or bed member which is formed, preferably, from sheet metal. The member 10 comprises a flat platen 11 provided with integral downward extending side flanges 12, the side

flanges 12 being provided with inwardly extending apertured lugs 13 in which rubber bumpers 15 are mounted (Fig. 4). The rubber bumpers 15 are adapted to support the improved duplicating device upon a stand, a table or any other suitable support.

At one end, the platen 11 is provided with spaced tongues or lugs 17 which are formed by cutting notches 18 in the platen 11. These tongues or lugs 17 have their outer ends cut off so that they do not project beyond the end of the platen 11. It will be noted that the platen 11 is curved downwardly as at 20 between the lugs 17 and between the lugs 17 and the side flanges 12. This construction enables the operator to register, without any difficulty, one end of a hectograph band, hereinafter described, with the tongues or lugs 17.

The other end of the platen 11 is also curved downwardly as designated by the reference character 22. This end of the platen 11 is provided with notches 25 aligned with the tongues or lugs 17. Also aligned with the tongues or lugs 17 are fingers or bars 26 which are slidably journaled beneath the platen 11 by transversely extending bars 27 and 28. The bars 27 and 28 may be secured to the underside of the platen 11 in any suitable manner such as, for instance, spot welding.

As best shown in Fig. 4, the inner end of each bar 26 is provided with an integral downwardly extending lug 30. A spring 31 is provided for each bar 26 and has one of its ends secured to the associated lug 30, the other end of the spring 31 being secured to a pin 32 projecting downwardly from the associated bar 28. It will be noted that the springs 31 urge the bars 26 outwardly to the right (Figs. 1, 2 and 4).

Between the bars 26 is an angle iron member 35 rigidly secured to the under surface of the platen 11.

Drawn taut over the platen 11 is a hectograph band which is designated generally by the reference character 36. It comprises a backing member 37 and a coating of gelatin 38. The backing member may be made of paper, fabric or any other suitable material. Clamped to the ends of the paper backing 37 are reenforcing members 39 and 40 which are preferably formed from sheet metal and are preferably identical in construction so that the ends of the band 36 are interchangeable. In other words, either end of the hectograph band 36 may be associated with either end of the platen 11.

The construction of the reenforcing members 55

39 and 40 is best illustrated in Figs. 4 to 7, inclusive. It will be noted that each of the reenforcing members is bent to provide a U-shaped portion 42 clamped upon one end of the backing member which is folded to provide a tongue 43 projecting into the associated U-shaped portion 42. The ends of the backing member 37 are also clamped between the U-shaped portions 42 and tongues 44 which engage the bottom surface of the backing member 37. The tongues 44 are bent intermediate their ends to provide pockets 46 which will register with the lugs 17 and the bars 26 when the hectograph band or pad 36 is secured to the platen 11 in the manner illustrated in Figs. 1, 2, 4, 6 and 7. It will be noted that the pockets 46 co-operate with the lugs 17 and the bars 26 to aline the side edges of the hectograph pad 36 with the side edges of the platen 11.

20 When the hectograph pad 36 is to be secured to the platen 11, the pockets 46 at one end of the hectograph pad are alined, preferably, with the outer ends of the bars 26 and then the operator grasps the angle member 35 and employing it for leverage, displaces the reenforcing member 40 to the left (Figs. 1 and 2) against the action of the springs 31 so that the pockets 46 in the reenforcing member 39 may be engaged with the lugs 17. The operator then releases the reenforcing member 40 and the springs 31 yieldingly urge the reenforcing member to the right (Figs. 1 and 2) until the hectograph pad 36 is drawn taut over the platen 11. The hectograph pad may then be moistened and employed in the usual manner. Preferably, a rubber roller is utilized to press the masters and copy sheets against the duplicating surface of the hectograph pad. It will be noted that the curved upper surfaces of the ends of the platen 11 and the side edges of the notches formed

therein guide the reenforcing members into alinement with the lugs 17 and the bars 26.

I claim:

1. Hectograph apparatus comprising a platen, lugs projecting from one end of said platen, said end of said platen being curved downwardly intermediate said lugs, the other end of said platen being provided with notches alined with said lugs, said other end of said platen being curved downwardly intermediate said notches, spring-pressed bars alined with said notches, and a hectograph band, and reenforcing members on the ends of said band, said reenforcing members being provided with pockets engageable by said lugs and said spring-pressed bars to hold said band taut over said platen, said curved ends of said platen serving as guides to bring said pockets into positions wherein they are engageable by said lugs and said spring-pressed bars.

2. Hectograph apparatus comprising a platen having a plurality of pairs of notches in one end thereof, a lug projecting from said end of said platen between the notches of each pair thereof, said end of said platen being curved downwardly between and at either side of said lugs, the other end of said platen being provided with notches alined with said lugs, said other end of said platen being curved downwardly, spring-pressed bars alined with the last-mentioned notches, and a hectograph band, and reenforcing members on the ends of said band, said reenforcing members being provided with pockets engageable by said lugs and said spring-pressed bars to hold said band taut over said platen, said curved ends of said platen serving as guides to bring said pockets into positions wherein they register with said lugs and said spring-pressed bars.

JOHN W. HERNLUND.
